UNITED STATES PATENT OFFICE.

ALFRED GODFREY, OF WOOD GREEN, LONDON, ENGLAND.

JET-CUTTING MACHINE.

Application filed January 16, 1923. Serial No. 613,066.

To all whom it may concern:

Be it known that I, ALFRED GODFREY, a British subject, residing at the Godfrey Engineering Works, Boundary Road, Wood Green, in the county of London, England, have invented certain new and useful Improvements in Jet-Cutting Machines, of which the following is a specification.

This invention relates to cutting by oxy-acetylene or like jet cutting processes.

The object of the invention is to provide improvements whereby the utility of the process may be increased and more particularly to enable cuts of very great length (limited only by the length of a stationary slideway) to be carried out to a predetermined profile with a high degree of accuracy. A further object is to enable not only a profile but variously shaped holes and apertures circles and bevelled edges to be cut on the same machine by means of combined straight, irregular (or template guided) and circular feeds without resetting the work-piece. In each case, whatever feed motion of the jet (except circular) is employed the actual cutting speed may be set to a predetermined required speed and remains constant for that setting.

I have already, in my prior U. S. Patents 30 Nos. 1,357,859 issued Nov. 2, 1920, and 1,431,650 issued Oct. 10, 1922, described machines with a jointed arm permitting of universal motion in one plane and supporting a cutting blowpipe head and mechanical means to drive the cutting head along a path determined by the shape of a template. These machines are, however, limited as to the length of cut obtainable at one setting by the reach of the jointed arm: other machines 40 within my knowledge are either special-purpose machines or portable machines, or are similarly limited in range or scope. So far as I am aware a jet cutting machine capable of a practically unrestricted range and variety of work, so as to make any required profile or aperture on plates up to any required size such as is contemplated in connection with the present machine is entirely new, and it is an important feature of the 50 invention that it provides a machine whereby large jobs such as locomotive frames can be cut out completely by the jet process, including all profiles and apertures.

The present invention consists in the improved machine as a whole and in improvements embodied therein: an important fea-

ture is the use of a travelling truck or carriage carrying the gas cylinders and controls and preferably also the motor or like source from which power is transmitted to the feed devices, so avoiding the use of enormous lengths of flexible piping and power shafting; it comprises the combination of a cutting head, a longitudinally slidable carrier adapted to support the cutting head through means permitting lateral motion thereof, and means to drive the cutting head along a profile determined wholly or in part by the shape of one or more templates.

It will be realized that a great variety of constructional embodiments may be devised to carry out the underlying idea, and while the invention further comprises the novel constructional features and combinations contained in the preferred forms hereinafter described it is not my intention to confine its scope to these particular forms.

In the form selected for illustration a jointed arm and a sliding arm to which rotary motion can be transmitted are both shown, each carrying a blowpipe and carried by a laterally sliding carriage.

Referring to the drawings:—

Fig. 1 is an elevation of the machine, looking in the longitudinal direction.

Fig. 2 is a plan of the blowpipe carriage with the template-engaging gear removed.

Figure 3 is a front elevation of the same with the means for driving along the template in position.

Fig. 4 is a detail of the longitudinal feed device.

Fig. 5 is a plan of the template-engaging device.

Fig. 6 is a side elevation showing the blowpipe carriage and the transmission of the drive to the longitudinal feed.

Fig. 7 is a side elevation of a central pedestal and table adapted to adjust the height of the work when stationary or to rotate the work for the purpose of making angular adjustment or very large circular cuts.

Fig. 8 is a sectional elevation of the same.

Fig. 9 is a plan partly in section of the pedestal and bottom thrust bearing of the same.

Fig. 10 is a plan showing the same with the table and its worm wheel removed.

Figs. 11, 12 and 13 illustrate a modified form of gas-cylinder truck in greater detail than is possible in Fig. 1 and also illustrate the means whereby surplus lengths of flex-

ible piping may be conveniently dealt with.

Referring to the drawings a longitudinal girder 1, which together with the plate 2 forms a longitudinal slideway, is supported by cross-girders 3 on pillars 4, and may be extended to any required length; I prefer to make it in units of from 20 ft. to 40 ft. A lateral slideway 5 is suspended from the plate 2 by means of rollers 6, 6 and has a feed roller 7 (as shown a friction roller, but a toothed pinion and rack might be employed) adapted to feed it bodily along the longitudinal slideway. A carriage 8 with an extension 8^a runs along the slideway 5 on rollers 9, 9 and lateral guide rollers 10, 10 (see Figures 2, 3 and 6). The cutting head or blowpipe nozzle 11 has limited vertical motion within a sleeve 12 provided with a rigid extension 12^a slidable within a rotary head 13 and adapted to be slid along horizontally within the same by means of a feed screw 14 and hand-wheel 5.

It may be noted here that by angular and axial adjustment respectively of the head 13 and the extension 12^a the cutting head 11 has a large range within which it may be moved to any required position relatively to the carriage 8.

Four alternative power feed devices are transmitted through the carriage, the power to all being supplied through the flexible-shaft 15, pinion 16, tumbler gears 17 (forward) or 18 (reverse) and driven wheel 19 mounted on a splined or like shaft 20: Figs. 3 and 6 show the drive in neutral position; forward and reverse are engaged by the action of inclined faces formed in the bar 21 on the corresponding projection 22 of the tumbler frame 23. The bar may be moved either by the hand lever 24 or by the contact of the carriage with adjustable stops 25, 25 arranged to be slidden along the bar 21 into any required positions and there clamped by thumbscrews 25^a.

Starting from the splined shaft 20 the four feeds are as follows:—

(1) Longitudinal, through bevel wheels 26 and 27, inclined shaft 28, worm 29 (carried by pivoted frame 30 and held in engagement with worm wheel 32 by a spring 33) and feed roller 7, which with the reaction roller 7^a is also spring pressed by spring 33 and released by rotation of knot 31 with cam 32 extending the spring and raising the roller 7 out of contact with plate 2.

(2) Lateral, through worm 34 and worm-wheel 35, hollow spindle 36, toothed clutch 37 (when in downward position as shown) pinion 38 and toothed rack 39. A handle 40 is also shown to give a quick movement along the rack for setting through bevels 41 and pinion 42.

(3) Circular, through worm 34 and worm-wheel 35, spindle 36, clutch 37 (when in up-

per position, reached through a neutral by raising lever 43 and thereby rotating the eccentric pin 44 working in the groove shown in the clutch member 37), gear wheels 47 and 48 and spindle 49 to head 13 and extension 12^a.

(4) Irregular (or by overhead template), through worm 34, wormwheel 35, cone clutch 50, spindle 45 and feed roller 46, mounted as shown with the spring pressed idlers 51, 51.

It may be noted that the above feeds are all thrown into forward, free or reverse position by the lever 24, and all are derived from one flexible transmission shaft 15 (or a telescopic shaft with universal joint) and thence through a single splined shaft 20. Moreover the ratios of the gears and worms and the sizes of the feed rollers are so chosen that for any given speed of the shaft 15 the speeds of each straight feed and that of the irregular feed are the same: the circular feed is driven through gearing 47, 48 of the approximate ratio of 1 to π (say 1 to 3 or 7 to 22) so that the length of cut 90 equivalent to π revolutions of the pinion 38 gives one revolution of the head 13. In this manner the actual cutting speed when the circular feed is employed is also the same as that of the other feeds for unit diameter, 95 and for any given setting of the driving speed the circular cutting speed is in the simple ratio of actual diameter of circular cut to unit diameter: this relationship of angular speed in the circular cutting device 100 to linear speed in the others is for convenience referred to hereinafter as a constant actual cutting speed.

A jointed (or it may be pivoted and telescopic) arm 52 is also adapted to carry a blowpipe 11^a which, as illustrated has been adjusted to cut a bevel edge, and which may be similar to or interchangeable with the blowpipe 11. In each case the blowpipe may have a limited vertical movement and be actually supported from the surface of the work by alternative and removable and adjustable rollers 53, 53; or where the work is sufficiently flat may be suspended at a definite but adjustable height. The arm 115 may be freed and a suitable portion immediately over the blowpipe pressed against suitable templates (either stationary or revolving) while one of the feeds is engaged or while work is rotated on the central table, or it may be set and fixed by screws 54, 54 in any required position relatively to the carriage 8, thus very considerably increasing the lateral range of a given length of lateral slide. Referring for example to Fig. 1 it will be seen that the single template 55 that is shown can regulate the cutting of its profile starting from any point within the extreme lateral and longitudinal reach of either the extension 12^a or the arm 52. The 120

template is shown of bent angle section with a depending flange gripped on both sides by the feed roller 46 and idlers 51, 51 mounted on pivoted arms 56, 56 (see Fig. 5) extensions 56^a, 56^a being spring-pressed apart to press the three rollers together. Such a group of rollers may be quickly set in position on the template and removed by gripping the said extensions. As an alternative 10 when cutting long moderately straight profiles the carriage may be continually pressed in one lateral direction so as to hold the feed roller against the edge of the template. It is to be understood that a single template 15 will rarely be used for the whole of a very long profile, as heat expansion or other causes may lead to inaccuracy: it is preferable where straight feeds can be employed to use them and to mark out irregular portions 20 on the work-piece so that the blowpipe may be made to coincide with the proper spot before the portion of irregular feed work is proceeded with.

Referring now to the devices for supplying power and gases to the machine a truck 25 60 is shown running on rails 61, 61 parallel to the main girder 1. Gas cylinders 62, 62, 63 and the gas controlling devices usually formed rigidly with the blowpipe head and indicated at 64 are mounted on the truck 30 and connected to the cutting head 11 or 11^a by flexible piping 65. A motor or other source of power 66 drives a frictional reducing variable gear box 67, from which 35 the drive is transmitted through a second similar box 68 to the flexible driving shaft 15, so obtaining a great range of speed, infinitely variable. A pinion 69 also transmits the drive through gear wheel 70 and worm 40 gear 71 to a friction roller 72 which may be caused to drive the truck by being pressed against the rail 61 by means of an eccentrically mounted roller 73 actuated by the hand lever 74. The ratios and sizes are so chosen 45 that the speed of the truck, while its feed is engaged, is the same as the longitudinal feed speed of the cutting head for the same gear box setting.

In order to avoid any trouble with surplus lengths of flexible connections I provide means upon the truck to take up whatever surplus there may be as the blowpipe approaches the truck. For example a bracket 100 may be secured to the blowpipe 50 carriage with a fixed sector 101 a short distance from the blowpipe. The flexible leads 65 rest against the said sector and are carried thence round a pulley 102 mounted upon a subsidiary truck 103 and a fixed pulley 104, mounted on the operating truck, 55 on their way to the gas control devices 64. The truck 103, with pulley 102, by its motion towards or away from the blowpipe on the extended table 105 takes up or releases whatever length of the leads may be necessary 60 65

and may be so counterweighted, by means of a cord 106 attached to its mounting and to the subsidiary truck 103 and carried over a vertical guide pulley 107, as to retain them always slightly under tension. To avoid 70 confusion the word "truck" is used to denote the device on which the cylinders are carried but any form of sliding carriage is to be understood to be included in the term.

The operator may conveniently stand 75 upon the platform 60^a during the greater part of the operations of the machine.

Referring now to the pedestal and table more particularly detailed in Figs. 7 to 10, the drive may be derived by attaching the flexible shaft 15 or from an independent source to a similar tumbler gear device (indicated at 75) to that already described in connection with the carriage 8. It is thence transmitted through suitable reducing gears to a worm 76. The above gearing is carried by a box 77 pivoted at 78 and drawn by a spring 79 against an adjustable stop 80, so keeping the worm 76 normally in engagement with the worm wheel 81 attached to the table 82. Raising and lowering is effected by means of a handwheel 83 mounted on a splined shaft 84 which passes through wheel 85 engaging pinion 86 and thereby driving the worm 87 which engages 90 the worm wheel 88 and so rotates the screw 89 within the nut 90, so raising the sleeve 91 and the gears bearings and table carried thereby. It will be clear that the very large range of plates, possibly comparatively 95 small but possibly extending many feet, which the table is intended to handle would make it almost impossible to manipulate ordinary control levers. Accordingly the hand wheel 83 and levers 92 and 93 are all 100 mounted on splined shafts which may be drawn out from the table for the appropriate distance to suit any particular plate. Lever 92 on shaft 92^a is arranged to raise 105 the inclined end 94^a of rod 94, thereby engaging a roller 96 carried by the gear box 77, causing the latter to rotate about its pivot extend the spring 79 and release the worm 76 from engagement with the worm-wheel 81. Lever 97 on shaft 97^a rotates the 110 crank 98 and so raises or lowers the rod 99 which actuates the tumbler gear 75 to give forward or reverse speed.

As an example of the use of the machine 115 I will briefly describe the operation of cutting out a locomotive side frame having one long straight side cut back in two or three places, a number of apertures of circular and irregular shape, perpendicular ends and a side consisting of stepped parallel portions. The plate from which the frame is to be cut is first set up horizontally with its top surface at a predetermined height, the immediate supports preferably consisting of pillars or blocks situated out of the 120 125 130

- way of any of the required cuts. Starting at one end one blowpipe is set along the transverse slide to the required position for the straight longitudinal cut and locked.
- 5 The longitudinal feeds of cutter and truck are then engaged and the cut proceeds at predetermined speed until one of the recesses is reached. The feed roller and idler above the cutter (if a free jointed arm is used) or anywhere on the head (in other cases) are then engaged with a portion of template conforming (after allowing for the size of the roller) to the shape of the recess, the jointed arm (or both slides as the case may be) being temporarily freed and the feed motion of the truck discontinued as required. As the cutter comes to the end of the recess and re-enters the straight portion the parts are again locked and the 10 straight feeds of slide and truck re-engaged. All recesses or curved portions or apertures may be cut by means of circular feeds or templates set up in predetermined positions while it is generally more convenient to use 15 the straight feeds for any considerable 20 straight cuts.

It will be understood that the apparatus is primarily intended for (though not limited to) cuts of a length of ten or twenty 30 or forty feet or more. The length of cut which can be effected is only limited by the length of the longitudinal slide which may be manufactured in standardized lengths of which sufficient may be employed in any 35 particular case for the maximum length required.

I claim:—

1. In a jet-cutting machine the combination of a slideway, a sliding member adapted to slide thereon, an arm mounted from said sliding member said arm having a plurality of vertical pivotal joints, a blowpipe carried by the arm, and a superimposed guiding template above the blowpipe.
- 40 2. The combination set forth in claim 1, with means to feed the blowpipe transversely at right angles to the slideway.
3. In a jet-cutting machine a slideway in combination with a cross-slide suspended 50 therefrom, forming a compound slide, a blowpipe free to move along both slides and thereby supported for free movement in a plane with the slides in fixed angular relationship, and a superimposed template 55 above the blowpipe to guide the course of the said blowpipe.
4. In a jet-cutting machine a blowpipe, an arm carrying said blowpipe, said arm having a plurality of vertical pivotal joints, a 60 carriage supporting said arm, and a compound slide supporting said carriage.
5. A jet-cutting machine having a blowpipe and mechanical means to support said blowpipe for motion in a plane in combination with an independent means adapted

to carry heavy parts and to be moved in substantial conformity with the movement of the blowpipe.

6. A jet-cutting machine having a blowpipe, means to support said blowpipe for 70 longitudinal and transverse movement, an independent longitudinally movable truck carrying heavy parts, flexible connecting means between said parts and the blowpipe, and transversely moving means on said truck to take up surplus lengths of said connecting means.

7. A jet-cutting machine having a longitudinal slideway, a blowpipe, laterally movable means carrying said blowpipe and supported from said slideway, a second longitudinal sliding device moving parallel to said slideway, a source of power carried by said second sliding device, and means to transmit the power from said source to 80 effect the movement of said blowpipe.

8. In combination with a jet-cutting machine having a longitudinally and laterally movable blowpipe, a source of power, variable speed gearing, and gas storage means, 90 a longitudinally movable truck carrying said gearing and storage means, connections transmitting the power to the machine for operating the blowpipe, flexible gas connections to the blowpipe and means for automatically taking up slack in said gas connections.

9. A jet-cutting machine having a very long main longitudinal blowpipe-feed device in combination with independent means 100 for carrying the heavy parts (such as those described) substantially parallel with the blowpipe from one end of the machine to the other.

10. A jet-cutting machine including the 105 combination of a compound slide, and a blowpipe supported thereby in one plane, with a rotary feed device having movement independently of the blowpipe and adapted to rotate relatively to the slides in a parallel plane.

11. A jet-cutting machine including the combination of a compound slide, and a blowpipe supported thereby in one plane, with a rotary mechanically fed work-table.

12. A jet-cutting machine comprising a blowpipe, a longitudinal slideway, rollers engaging said slideway, a transverse slideway supported by said rollers, further rollers engaging said transverse slideway, a carriage supported by said further rollers, a blowpipe maintained in one plane by said carriage, a template above said carriage, and feeding means to draw said blowpipe along a path determined by said template.

13. A jet-cutting machine comprising a blowpipe, a rotary feed device, a pivotally jointed arm supporting said blowpipe (giving it independent motion in the same plane), and a compound slide having a car-

riage supporting both said feed device and said pivotally jointed arm.

14. A jet-cutting machine including the combination of a compound slide, a rotary feed device carried thereby, an arm having a plurality of vertical pivotal joints, a blowpipe supported from the same slide as the said feed device through the intermediary of said pivotally jointed arm, and 10 a template against which the blowpipe may be pressed while the feed device is engaged.

15. A jet-cutting machine for cutting out complete locomotive frames or similar large jobs including mechanical feeds to effect 15 straight longitudinal cuts, transverse cuts, circular cuts and template-guided angular or irregular cuts, means to support a blowpipe in one plane comprising a longitudinal slideway and a lateral slideway, and means 20 to apply any of said feeds to said blowpipe in any position within range of said slide-ways.

16. A jet-cutting machine comprising in combination a longitudinal slide, a blow- 25 pipe, means to support said blowpipe from said slide through means permitting lateral motion of the blowpipe, a superimposed template corresponding to the profile to be cut, means engaging the said template, and 30 means to feed the blowpipe along the said profile at a substantially constant speed.

17. A jet-cutting machine comprising in combination a longitudinal slide, a jointed arm supported therefrom and adapted to 35 swing in a horizontal plane parallel to the movement thereof, said arm having a plurality of parallel pivotal joints, and a blow- pipe carried by said jointed arm.

18. A jet-cutting machine comprising a 40 carriage, a blowpipe adapted to be guided by said carriage, a lateral slideway for the carriage, a longitudinal slideway supporting the lateral slideway, a template fixed over the carriage, and a driven feed roller with 45 its axis fixed relatively to the carriage and adapted to drive the same at any predetermined speed within a wide range along a contour set by the template.

19. In a jet-cutting machine the combi- 50 nation of a slideway and a blowpipe-guiding carriage supported thereby with driving means, a separate truck carrying said driving means and running parallel to said slideway, said driving means being adapted 55 to be connected to mechanical feed devices for driving the first named carriage.

20. A jet-cutting machine having means to vary the speed of the drive and alterna-

tive straight and irregular feeds, so ar- ranged that the speed of the jet along the 60 path to be cut is substantially constant (for any given setting of the speed varying means) whichever feed is employed.

21. A jet-cutting machine having a blow- 65 pipe, an overhead guiding member, an over- head slideway, a lateral slide adapted to slide thereon and to carry said blowpipe and a frictional driving and gripping de- vice fixed relatively to the position of the blowpipe and adapted to grip said overhead 70 guiding member and thereby to drive the blowpipe at a constant speed along any path predetermined by the shape of the said guiding member.

22. In a machine of the kind described, 75 a mechanically operated table and adjust- able controlling devices for said table adapt- ed to be drawn away from or pushed to- wards the table to suit the convenience of 80 the operator according to the size and posi- tion of the work.

23. A jet-cutting machine including a 85 carriage having alternative longitudinal and transverse and irregular and circular feeds and a single control lever which engages, 90 disengages and reverses all feeds.

24. In a jet-cutting machine, the combi- 95 nation of a blowpipe, a support therefor adapted to swing in a horizontal plane and consisting of a linked arm composed of a 100 plurality of vertically disposed sections; a slidable mounting for said support consist- ing of a carriage adapted to travel horizon- tally upon a slideway, an overhead trans- verse frame adapted to suspend the slide- 105 way and to permit the carriage to move freely therealong, the blowpipe-supporting arm being free to swing beneath said slide- way.

25. In a jet-cutting machine, the combi- 110 nation of a burner-nozzle vertically sup- ported over the work-piece by a horizon- tally-swinging linked arm of variable op- erative radius adapted to move above said work-piece, said arm being vertically piv- oted to a horizontally slidable carriage; a 115 horizontal slideway extending transversely above the linked arm and supporting said carriage, a horizontal bridge member ex- tends transversely above said slideway; and suspending means between said bridge member and said slideway permitting hori- zontal movement of the latter in a direction angular to the direction of its length.

In testimony whereof I affix my signature.

ALFRED GODFREY.
